CLAIM

The ornamental design for a public access computer and cell phone communication system, as shown and described herein.

DESCRIPTION

FIG. 1 is a perspective view of my inventive public access computer and cell phone communication system.

FIG. 2 is a front elevational view thereof.

FIG. 3 is a rear elevational view of the communication system.

FIG. 4 is a top perspective view of my novel design.

FIG. 5 is a side elevational view thereof; and,

FIG. 6 is a view, similar to that of FIG. 5, however showing a variable position capacity of the solar panel array thereof. The broken away portions of the drawings indicate the appearance of any portion of the article between the break lines and form no part of the claimed design.
